UNITED STATES PATENT OFFICE.

JAMES S. SHORTLE, OF CHICAGO, ILLINOIS.

SIPHON-HEAD.

SPECIFICATION forming part of Letters Patent No. 597,834, dated January 25, 1898.

Application filed May 10, 1897. Serial No. 635,846. (No model.)

To all whom it may concern:

Be it known that I, JAMES S. SHORTLE, a citizen of the United States, residing at Chicago, in the county of Cook and State of Illinois, have invented a new and useful Improvement in Siphon-Heads, of which the following is a specification.

My invention relates to siphon-heads for vessels in which liquids are stored and discharged under gas-pressure.

The objects of my invention are to attain simplicity and cleanliness in devices of this class; to provide a siphon-head which will be operative without the spring and spring-chamber in ordinary use on devices of this class, one which may be operated with a lower gas-pressure than is required by those in ordinary use, and one in which the entire body of the siphon-head is of such simplicity that it can be readily molded from glass, porcelain, or similar material; to provide for cleanliness by arranging the valve-actuating mechanism mainly outside of the body of the siphon-head; to provide for adjusting the valve-actuating mechanism out of the operative position, so as to avoid accidental discharge of the liquid, and to improve the construction of the valve and its actuating mechanism. I accomplish these objects by the mechanism illustrated in the accompanying drawings, in which—

Figure 1 is a vertical section of the upper part of a bottle 10, having a siphon-head constructed according to my invention secured thereto. The valve is closed in this view and the lever is shown in dotted lines laid back out of the operative position. Fig. 2 is the same view showing the valve open for the discharge of fluid. Fig. 3 is an outside view of the valve with its stem and the elastic collar 4.

The casing 7 or body of the siphon-head has the valve-chamber 7' therein, is provided with a discharge-chamber terminating in the nozzle 7", and a projection 6, furnishing a fulcrum-seat for the lever.

The casing 7 is suitably arranged for attachment to the vessel. This may be done by means of the divided collar 11, such as is in ordinary use, or it may be attached in any other convenient manner. It will be understood that same may be adapted for attachment to any desired form of vessel.

The tube 9 is held in an elastic hollow plug 8, having an annular recess for the flange on the tube and having an outer flange around the top of the plug serving as a gasket or packing between the top of the bottle-neck and the casing 7. The flange on the tube and the annular recess for same in the plug may be omitted, the lateral pressure of the plug 55 on the tube being usually sufficient to hold same in position. The object of this form of plug is to bring the top of the tube down substantially flush with the bottle. This is an advantage over those in ordinary use, where 60 the tube projects into the valve-chamber and the valve operates in an enlargement of the tube. A larger vent is provided in my construction without enlarging the body of the siphon-head. 70

The valve 12 is seated in the upper part of the chamber 7' and controls the passage from the vessel into the nozzle 7". The valve is provided with a stem 3, extending through the top of the casing and having thereon a 75 head 3'. Intervening the head 3' and the top of the casing is the elastic packing or collar 4, through which the stem 3 extends. This serves both as a spring for normally closing the valve and as a gasket or a packing for the 80 valve-stem. The lever 5 has its fulcrum in the projection 6. The projection 6 preferably extends higher than the head 3', so that when the lever is laid back in the position shown by the dotted lines the bottles may be packed 85 in boxes without danger of having the head 3' accidentally depressed and the valve thereby opened.

The valve consists of the body 1, of metal or some other hard material, having an annular recess, into which the elastic disk 2 is sprung. The piece 1 is threaded upon the stem 3, thus providing for ready attachment of the parts, as well as for adjustment of the valve either before or after the siphon-head 90 is secured to the vessel. This is done by turning the head 3', thereby screwing the stem in the body 1 of the valve. When the valve is closed, the disk 2 will be bent downwardly at its outer rim through its contact with the 95 walls of the upper narrow part of the chamber 7'. The lower flange on the member 1, formed by the annular recess, is preferably beveled on top, so that same firmly presses the 100

disk against the walls of the chamber when the valve is closed. The nozzle is preferably made so that it will slant downwardly from the top of the valve toward the discharge end. This prevents an accumulation of liquid above the valve. My valve is particularly adapted for this purpose, since the elasticity of the disk 2 permits the upper part of the valve to be drawn up flush with the lower wall of the discharge-chamber or with the base of the nozzle. The elasticity of the disk 2 also provides a broad contact of the valve with the walls of the upper part of the chamber 7', thus furnishing a very secure valve, requiring but little pressure to hold it in position.

I regard it as a particular advantage in my device to have the valve-actuating mechanism mainly on the outside of the siphon-head, so that the parts may be easily kept clean.

20 A feature of my valve connection is that the valve may be tightened from the outside by turning the head 3', thus providing a further safeguard against accidental discharge of the fluid in shipping. This, it will be seen, can be readily loosened again by the operator, so as to permit the free operation of the siphon.

The disk 2 is preferably made of rubber, and the contact of this with the walls of the chamber 7' prevents the body of the valve from turning when the stem is turned in the member 1.

30 It will be seen that a spring may be used in connection with my member 4; but I prefer to use this member without a spring, first, on account of cleanliness, and, second, because but little force is needed to close the valve, the same being held in position principally by the pressure of the gas.

The elastic members 2, 4, and 8 may be 40 readily replaced by others when worn or hardened through the action of the fluid or gases.

The other parts of the device may be made of metal or any other suitable material, such as porcelain. The simplicity of the member 7 particularly adapts same to be made of porcelain.

45 What I claim as my invention, and desire to secure by Letters Patent, is—

1. A siphon-head, comprising a body 7, having a valve-chamber and a discharge-chamber 50 with a passage between same; a valve in said valve-chamber for controlling said passage; a stem secured to said valve extending through said passage and through the opposite wall of the discharge-chamber, and terminating in a head outside of said body; said head and valve being adjustably connected by said stem; an elastic collar on said stem between the head and said wall for normally urging the stem outward so as to close the valve; and a lever 55 for depressing said head; substantially as described.

2. A siphon-head, comprising a body 7, having a valve-chamber and a discharge-chamber with a passage between same; a valve in 60 said valve-chamber for controlling said passage; a stem threaded to said valve, extending through said passage and through the

opposite wall of the discharge-chamber, and terminating in a head rigidly secured to the stem outside of said body whereby said valve may be adjusted on the stem; an elastic collar on said stem between the head and said wall for normally urging the stem outward so as to close the valve; and a lever for depressing said head; substantially as described. 75

3. A siphon-head, comprising a body 7, having a valve-chamber and a discharge-chamber, with a passage between same; said valve-chamber being cone-shaped, with the narrow part toward said passage; a valve in said valve-chamber for controlling said passage; said valve consisting of the member 1 having thereon the elastic disk 2; a stem, secured to the member 1, extending through said passage and through the opposite wall of the discharge-chamber, and terminating in a head outside of said body; said head and valve being adjustably connected by said stem; an elastic collar on said stem between the head and said wall for normally urging the stem outward so as to close said valve; and a lever for depressing said head; substantially as described. 80

4. A siphon-head, comprising the body 7; a valve in said body having a stem extending through the outer wall of the body; an elastic member outside of said wall for normally urging said stem outward so as to close said valve; the projection 6 on said body near the stem; and a lever pivoted in said projection for depressing said stem, and adapted to be turned out of the operative position; substantially as described. 90

5. A siphon-head, comprising the body 7; a valve in said body having a stem extending through the outer wall of said body; an elastic member outside of said wall for normally urging said stem outward so as to close said valve; the projection 6, on said body, extending beyond the outer limit of the stem; and a lever pivoted in said projection, for depressing said stem, and adapted to be turned out of the operative position; substantially as described. 105

6. A siphon-head consisting essentially of a body 1; a valve in said body having a stem extending through the outer wall of said body, and terminating in an outer head; the elastic collar 4 on said stem, between the head and said wall, adapted to serve both as packing for the stem and as a spring for normally urging same outward so as to close the valve; the projection 6, on said body, extending beyond the outer limit of the stem and head; and a lever pivoted in said projection, for depressing said stem, and adapted to be turned out of the operative position; substantially as described. 115

7. A siphon-head, consisting essentially of the body 7, having the valve-chamber 7' therein, and a discharge-chamber above same; a passage between said chambers; a valve in said valve-chamber for controlling said passage; said valve consisting of the member 1 130

having thereon the elastic disk 2; a stem threaded to the member 1, extending through said passage and through the upper wall of the discharge-chamber, and terminating in a head 5 outside of said body; the elastic collar 4 on said stem, between the head and said wall, adapted to serve both as packing for the stem and as a spring for normally urging same upward so as to close the valve; the projection 6 on said

body extending above the limit of the stem 10 and head; and a lever pivoted in said projection for depressing said stem, and adapted to be turned out of the operative position; substantially as described.
